US0D1081745S

(12) **United States Design Patent** (10) **Patent No.:** **US D1,081,745 S**
(45) **Date of Patent:** **** Jul. 1, 2025**

(54) **CONNECTOR OF PACKAGING FOR FOODSTUFFS**

(71) Applicant: **Botrista, Inc.**, Dover, DE (US)

(72) Inventors: **Yu-Min Lee**, Taipei (TW); **Hui-Hsin Huang**, Taipei (TW); **Shih-Min Chan**, Taipei (TW)

(73) Assignee: **Botrista, Inc.**, Dover, DE (US)

(**) Term: **15 Years**

(21) Appl. No.: **29/937,602**

(22) Filed: **Apr. 16, 2024**

(51) LOC (15) Cl. **15-10**

(52) U.S. Cl.

USPC **D15/145**; D7/398

(57) **CLAIM**

The ornamental design for a connector of packaging for foodstuffs, as shown and described.

DESCRIPTION

FIG. 1 is a top, front, right side perspective view of a connector of packaging for foodstuffs showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front, right side perspective view thereof;

FIG. 9 is a top, front, left side perspective view thereof;

FIG. 10 is a bottom, front, left side perspective view thereof; and,

FIG. 11 is a bottom, rear, left side perspective view thereof. The broken lines in the figures show portions of the connector of packaging for foodstuffs that form no part of the claimed design.

The dot-dashed line in the figures defines the boundary of claimed and unclaimed objects, and the dot-dashed line forms no part of the claimed design.

1 Claim, 11 Drawing Sheets
